UNITED STATES PATENT OFFICE.

JAMES B. ROGERS, OF CHICAGO, ILLINOIS, ASSIGNOR OF ONE-HALF TO L. S. POWELL,
OF CHICAGO, ILLINOIS.

SPARK PLUG.

1,410,723.

Specification of Letters Patent. Patented Mar. 28, 1922.

Application filed June 17, 1918. Serial No. 240,301.

To all whom it may concern:

Be it known that I, JAMES B. ROGERS, a citizen of the United States, residing at Chicago, in the county of Cook and State of Illinois, have invented new and useful Improvements in Spark Plugs, of which the following is a full, clear, concise, and exact description, reference being had to the accompanying drawing, forming a part of this specification.

My invention relates to improvements in spark plugs, one of the objects of my invention being to provide a non-fouling spark plug. To this end I so construct my plug that only a small portion of the compressed gas of the explosive engine is first ignited in a confined space, whereby intense heat is developed about the electrodes of the plug and all carbon and products of combustion are entirely consumed, so that the electrodes of the plug always remain clean.

For the purpose of disclosing my invention I have illustrated one embodiment thereof in the accompanying drawings, in which—

Fig. 1 is a longitudinal sectional view of a spark plug embodying my invention;

Fig. 2 is a section taken on the line 2—2 of Fig. 1;

Fig. 3 is an elevation of the insulator of my plug;

Fig. 4 is an elevation of the lower electrode and its support;

Fig. 5 is a top plan view of the lower electrode support;

Fig. 6 is a perspective view of the upper electrode; and

Fig. 7 is a sectional view of the modified form of body of my spark plug.

In the embodiment of my invention illustrated, I provide a body 1 externally screw-threaded, as at 2, to screw into the engine cylinder. This body has a central chamber 3, which is a portion of the hollow core extending through the body and the side walls of which are curved on an ellipse. The insulator 4 is shouldered, as at 5, to rest upon the top of the body 1, and has another shoulder 6 which is engaged by the gland nut 7, through which the top of the insulator projects. The lower end of this gland nut is screw-threaded, as at 8, to engage on the screw-threads of the body, so that the insulator may be firmly clamped in position.

Preferably an asbestos washer 9 is inter-

posed between the shoulder 5 and the top of the body, and a combined asbestos and copper washer is interposed between the gland nut and the shoulder on the insulator. The insulator has extending centrally therethrough the conducting rod 10, on the lower end of which is mounted the forked electrode 11. This electrode is preferably formed of tungsten and the upper part thereof is countersunk in a suitable recess 12 in the insulator, suitable sealing matter being placed in the recess to form an air-tight joint at this point. The lower end of the insulator is hollowed or cored out to form an explosion chamber 13, in which is arranged the upper electrode 11. The sides of this chambered portion of the insulator have suitable openings or ports 14 therein. The bottom electrode 15 of the plug likewise has its upper end formed of tungsten and preferably takes the shape of a rod having an enlargement 16 formed thereon, which partially closes the bottom of the chamber formed in the insulator. The lower end of this rod is secured in and supported by a suitable support 17, which takes the form of a truncated washer in the form of a spider, the hub of which supports the bottom electrode and the rim of which is seated in the bottom of the body. The lower portion of the body is milled out to form a suitable seat for the rim of the support. After the rim has been placed in position the annular flange 18 left by forming the seat for the rim is turned over, securely locking the support in position. By truncating the spider support in the manner illustrated, larger openings are formed for the passage of the gas. The lower electrode is extended so that it occupies a position between the two forked ends of the upper electrode, so that the parts are always maintained in definite spaced relation and the danger of the contacts engaging by clamping the insulator in position is eliminated. The upper end of the insulator, where the conductor rod projects through, is recessed, as at 19, to receive a suitable filler to form at this point a gas-tight joint. The projecting end of the rod is provided with the usual nut 20 for attaching the conductor.

In Fig. 7 I have illustrated a modified form of body for my spark plug whereby means are provided for sighting the spark and also for priming, when desired. In this form of plug the body 1 is provided

2
with an annular flange 21, the side wall of which is chamfered off, as at 22. Mounted upon the body above this flange is a second movable ring 23, which screws upon the 5 threaded portion 24 of the body and has a chamfered face 25 co-operating with the face 22 of the ring 21. Extending through the ring and the side wall of the body is a port 24. It will be observed that by back- 10 ing off the ring 23 until the port 26 is exposed, a sight may be taken through this port to ascertain if the sparking electrodes are functioning properly; also, if desired, this port may be used for the purpose of 15 priming, by introducing a small quantity of gasoline through the port. When the spark plug is in use, however, the ring 23 is screwed tightly down, so that the co-operating faces 25 and 22 fit tightly together, 20 thereby closing the port 26.

In the operation of my plug, a portion of the compressed charge of the cylinder enters the chamber in the bottom of the insulator through the ports formed in the support 17 25 and through the ports 14. As soon as the electrodes become active the spark jumps from the tines of the upper electrode 11 to the lower electrode, thereby igniting the gas in the chamber. Due to the fact that the 30 gas is confined in this chamber and has not the opportunity to rapidly expand, a very intense heat is set up around the electrodes, which consumes all the products of combustion, and the electrodes, therefore, never 35 become fouled. The chamber surrounding the electrodes becomes at the moment of ignition of the gas an arc furnace developing a very intense heat. The ignited gases pass out through the port 14 and through the 40 openings in the support 7 to ignite the charge in the engine cylinder.

Having thus described my invention, what I claim as new and desire to secure by Letters Patent, is:—

45 1. In a spark plug, the combination with a body member adapted to be threaded into the wall of an engine cylinder, of an insulator supported in said body and having a chamber at its lower end, sparking electrodes arranged in said chamber and said chamber having ports in the side walls thereof.

55 2. In a spark plug, the combination with a body adapted to be threaded into the wall of an engine cylinder, of an insulator mounted in said body having a chamber in its lower edge, a forked electrode arranged within said chamber and a second electrode having a portion thereof lying between the 60 tines of the first electrode within said chamber, said chamber having ports in the side walls thereof.

3. In a spark plug, the combination with a body adapted to be screwed into an engine cylinder, of an insulator supported in

said body having a chamber at its lower end, an upper and lower electrode arranged in said chamber, and a support for the lower electrode comprising a truncated ported washer secured at the lower end of the body. 70

4. In a spark plug, the combination with a body adapted to be screwed into the cylinder of an engine, of an insulator co-operating with said body and having a chamber at its lower end, a forked upper electrode arranged within said chamber, a lower electrode extending between the tines of said upper electrode, and a support for said lower electrode comprising a truncated spider having a rim held in position in the 80 body and supporting the electrode on its hub.

5. In a spark plug, the combination with a body, of an insulator having a chamber at its lower end provided with ports extending through its side walls, a forked electrode mounted in the upper part of said chamber, a lower electrode, means for substantially closing the lower part of said chamber, and a support for said lower electrode comprising a truncated spider supporting the electrode at its hub and having a rim secured to the body. 85

6. In a spark plug, the combination with a body adapted to be screwed into an engine 95 cylinder, of an insulator supported in said body and having a chamber formed in its lower end provided with openings in the side walls thereof, the lower end of said insulator having its side walls spaced apart from the walls of said body, and sparking electrodes arranged in said chamber.

7. In a spark plug, the combination with a body adapted to be screwed into an engine cylinder, of an insulator supported in 105 said body and having a chamber formed in its lower end provided with openings in its side walls and being substantially closed at its bottom, the lower end of said insulator having its side walls spaced apart from the 110 walls of said body, and sparking electrodes arranged in said chamber.

8. In a spark plug, the combination with a body adapted to be screwed into a cylinder, of an insulator supported in said body and having a chamber formed in its lower end provided with openings in the side walls thereof, the lower end of said insulator having its side walls spaced apart from the 115 walls of said body, a sparking electrode supported by said insulator and arranged within said chamber, a second sparking electrode supported by said body extending into said chamber and having an enlargement substantially closing the lower end of said 120 chamber.

9. In a spark plug, the combination with a body, of an insulator mounted therein, an electrode supported by said insulator and an electrode supported by said body, one of 130

said electrodes having a forked portion within said insulator and the other having its end fitting between the tines of said fork.

10. In a spark plug, the combination with
5 a body, of an insulator mounted therein, an electrode carried by said insulator, a second electrode carried by the body, a shoulder on the exterior of said body having a chamfered face, said body having a priming 10 opening extending therethrough, an opening on said chamfered face, and a screw ring surrounding said body and having a chamfered face coinciding with the face of said shoulder.
- 15 11. In a spark plug, the combination with a body having a chamber formed therein

opening at the bottom, of an insulator having a chambered lower end arranged in said body chamber and provided with side openings in its walls, and electrodes arranged in 20 said insulator chamber.

12. In a spark plug, the combination with a body having a chamber formed therein opening at its bottom, of an insulator having a chambered lower end arranged in said 25 body chamber and provided with side openings in its wall and having its bottom substantially closed, and electrodes arranged in said insulator chamber.

In witness whereof, I have hereunto sub- 30
scribed my name.

JAMES B. ROGERS.
